VALVE

Application filed April 26, 1929. Serial No. 358,303.

This invention relates to valves and particularly to the poppet type of valve which is used in internal combustion engines.

One object of the invention is the provision of a valve having a hollow valve stem which contains two separate sealed chambers, one at the head end containing a quantity of cooling medium and the other being effective to substantially reduce heat transference from a middle portion of the valve to the stem tip.

Another object of the invention is the provision of a valve of the character mentioned which is formed by swaging the stem end together to concentrically restrict it, the intermediate portion of the valve stem having a restriction which partitions the space within the valve stem into two separate chambers, both of substantial size, the chamber at the head end of the valve containing a quantity of cooling medium which is liquid at the normal operating temperature of the valve to provide for efficient heat transfer by turbulent action of the liquid.

Further objects and advantages of the invention will be more fully set forth in the following description and in the accompanying drawings, in which—

Fig. 1 is a longitudinal section of a valve at one point in the course of manufacture;

Fig. 2 is a longitudinal section of a valve and guide embodying the present invention; and

Fig. 3 is a sectional view of a slightly modified form of construction.

In the manufacture of poppet valves used in internal combustion engines such valves are frequently constructed so as to contain a quantity of cooling medium which is liquid at the normal operating temperature of the valve, and which acts to transfer heat from the valve head to the valve stem portions remote from the head by turbulent action of the medium. The space within the valve stem is only partly filled with this cooling medium, which may be metallic sodium, or a mixture of salts of potassium nitrate and lithium nitrate or of other salts of the alkali metals having a melting temperature well below the normal operating temperature of

the valve. Such a valve construction is particularly desirable and effective in the exhaust valves which often operate at quite high temperatures, particularly exhaust valves of high-speed engines where lightness is an important factor.

In accordance with the present invention the valve stem contains two separate chambers, one containing a quantity of cooling medium and located adjacent the head end of the valve, the other chamber being empty and located towards the stem end of the valve. Referring more particularly to the drawings by reference numerals, in which like numerals designate like parts in the various views, 10 indicates a valve having a head 11 and a stem 12, the stem having a restriction or partition 13 between the head and the stem end. This partition 13 separates the space within the valve stem into the chambers 14 and 15 both of which are of substantial size, as shown. The chamber 14, which preferably extends into the head of the valve, is partly filled with a quantity of suitable cooling medium, sodium for example, or an eutectic mixture of potassium and sodium nitrates having a melting temperature well below the normal operating temperature of the portions of the valve with which the medium is in contact. Preferably a considerable quantity of such medium is used, but not enough to fill the space, so that the medium will be in a violent state of turbulence when the valve is operating, and effectively transfer heat from the valve head to the portions of the stem more remote from it.

It has been found in accordance with this invention that the cooling of the valve head is carried out effectively if the cooling medium chamber does not extend completely to the valve tip, but terminates at a point about midway of the valve so that at the head end of the valve stem there will be an effective transfer of heat from the head while the stem end of the valve does not reach such high temperatures as the portions closer to the head. With such a construction the valve guide will extend towards the stem end of the valve past the cooling medium

chamber so that the portion of the valve stem which is in contact with the stem tip side of the valve guide is not as hot as the portion of the stem which engages the valve head end of the guide. The valve head end of the guide will thus effectively carry away the heat of the comparatively hot head end of the valve stem while the portions of the guide in contact with the stem tip portion 10 of the stem is substantially cooler. The stem tip end of the guide and the portions of the stem operating therein, being considerably cooler than the hot head end causes a very substantial reduction in wear of the parts, 15 and the valve stem and valve guide life are lengthened. The heat is transferred rather slowly from the intermediate portion of the valve stem to the valve tip as the wall of the valve is considerably reduced at this portion, and as the chamber at the valve tip end 20 is filled with air which transfers heat at a comparatively slow rate. The valve springs adjacent the valve tip thus operate at a lower temperature and their effective life is thus increased, as the portion of the valve stem which they surround is not excessively 25 hot.

In the form of construction shown in Fig. 2 the valve may be made by first making a 30 metal valve part as shown in Fig. 1, comprising the head 11 and the stem portion 12 which is constructed with the enlargements 16 and 17, there being a cylindrical bore 18 extending through the stem almost completely up to the valve head. This part may then be swaged into the form shown in Fig. 35 2, the enlargements 16 and 17 being swaged concentrically inwardly to produce the portion 20 of partition 13 and portion 21 adjacent the valve tip. This leaves the outside 40 surface of the valve stem substantially cylindrical. The restricted openings 24 and 25 may then be drilled if necessary, and reamed preferably with a slight taper, and the outer 45 surface of the valve stem is finished, a suitable groove being provided at the stem tip portion thereof to receive the hollow collar customarily employed. The cooling medium 26 is then inserted into the chamber 14 through the open restricted stem end. This 50 medium may be inserted as a powder, or as a liquid or a plastic solid. When inserted as a powder the valve may be heated to reduce the powder to a liquid state, so that when 55 the valve again cools the liquid will freeze in the head end of the valve 14 which of course is held downwardly for this purpose. This holds the cooling medium in the chamber 14 while the chamber is being sealed, but of 60 course it is unnecessary to carry out this step if the head end of the valve is held down during the sealing operations which will now be described.

The restricted openings 24 and 25 having 65 been reamed, a tapered pin 27 is applied

through the open stem tip, this pin or plug having been machined and ground to a proper seat fitting the restricted opening 24 so that when it is driven or forced into place the two chambers 14 and 15 will be separated or sealed apart, and the cooling medium will be maintained in the head end of the valve at all times. Preferably the pin 27 is ground to fit the seat 25 in the stem end of the valve to seal the chamber 15 as well as the cooling 70 medium chamber 14. The chamber 15 being empty will not cause the transfer of heat to the portion of the valve stem near the tip, but the space within the stem tip end will give the advantage of lightness while providing for sufficient heat transfer which, combined with the more effective heat transfer at the head end of the stem will maintain the valve head comparatively cool and prevent burning or breaking of the valve. 75 After the pin or plug 27 is in place, a stem tip 29 of hard steel is preferably welded at 30 on the end of the stem, holding the pin permanently in place, and providing a hard surface which may receive the impact and pounding due to the operation of the valve 80 without wear or damage. The main portion of the valve may be made of iron or steel of a suitable composition so that the swaging operation may be conveniently effected, and so that the head end of the valve may resist the heat to which it is subjected. If the valve stem is constructed of hard steel a separate steel tip need not be applied, as it has been found that the pin or plug 27 will maintain 85 the seal of the cooling medium chamber, under normal operating conditions, merely by its driven connection in the tapered seat.

In Fig. 3 there is shown a slightly modified form of construction, a restriction in this valve being provided as indicated at 32 so as to separate the chamber 33 at the head end of the valve from the empty chamber 34 at the stem end of the valve. The chamber 33 contains the cooling medium 36 which partly fills this chamber and operates preferably by turbulent action in the manner previously referred to. The valve is preferably made by forming a part having an outward enlargement at the tip which may be swaged concentrically inwardly to provide the tip restriction 37. Before this swaging takes place however a metal cylinder, somewhat in the form of a small metal bag 38 is inserted through the open stem end of the valve, the cooling medium in the proper amount having been first added to the valve stem. After the bag 38, which may be of steel or other metal having the desired properties, is inserted in the stem end of the valve, the enlargement on the stem end of the valve part is swaged concentrically inwardly which reduces or constricts the open outer end of the bag 38, and seals this end. When the swaging operation is completed the entire 100 105 110 115 120 125 130

end of the valve is tight, and the cooling medium is confined to the head end of the valve space. Even if some leakage of the cooling medium does take place along the sides of the bag 38, it will be impossible for this leakage to find its way into the bag 38 since to do so it must travel all the way out to the end of the valve stem before gaining admittance. To provide a hard tip for the valve and a permanent seal for the chambers, a steel tip 39 may be welded or otherwise fixed on the valve end, this welding of course permanently sealing any cracks or minute passages which might be present, and through which the cooling mixture might pass.

While the valves herein described, constitute preferred embodiments of the invention, it is to be understood that the invention is not limited to the precise forms, and that changes may be made therein without departing from the scope of the invention which is defined in the appended claims.

What is claimed is:

1. A valve for internal combustion engines having a closed chamber in the head end of the valve stem containing a quantity of cooling medium, the valve having a sealed empty chamber of substantial size at the stem end thereof which effectively reduces heat transference from a middle portion of the valve stem to the stem tip.

2. A valve for internal combustion engines having a longitudinally extending closed space in the stem portion extending to a point near the stem tip, a partition in said space spaced from the stem tip dividing said space into two sealed chambers both of substantial size, and a quantity of cooling medium partly filling the chamber at the head end of the valve.

3. A valve for internal combustion engines having a longitudinally extending closed space in the stem portion extending to a point near the stem tip, means insertable through the stem tip partitioning the head end of the space from the stem tip end thereof to divide said space into two separate sealed chambers of about the same length, and a quantity of cooling medium which is a liquid at the normal operating temperature of the valve partly filling the chamber at the head end of the valve.

4. A valve for internal combustion engines having a longitudinally extending closed space at the stem portion extending to a point near the stem tip, means inserted through the stem tip for partitioning the head end of the space from the stem tip end thereof to form a head end chamber and a separate sealed stem tip chamber both of substantial length, a quantity of cooling medium partly filling the head end chamber, and a tip permanently applied at the end of the stem holding said means in place.

5. An exhaust valve for internal combus-

tion engines having a closed chamber in the head end of the valve stem containing a quantity of cooling medium, the valve having a hollow empty sealed chamber of substantial size at the stem end thereof which effectively reduces heat transference from a middle portion of the valve stem to the stem tip, and a valve guide for said valve extending toward the stem end to a location opposite the hollow empty chamber.

6. A valve for internal combustion engines having a longitudinally extending closed space at the stem portion extending to a point near the stem tip, a hollow metal bag in the stem end portion of said space partitioning the valve head end of the space from the stem tip end thereof to form a head end chamber and a separate sealed stem tip chamber both of substantial lengths reducing heat transference from a middle portion of the stem to the stem tip, and a quantity of cooling medium partly filling the head end chamber.

7. A valve for internal combustion engines having a longitudinally extending space within the stem portion extending to a point near the stem tip, the walls of the valve stem being thickened at a middle portion and at the stem tip end thereof, and plug means in the thickened portions of the stem wall tightly closing the thickened portions of the wall and providing a head end chamber and a separate sealed stem tip chamber both of substantial length reducing the heat transference from a middle portion of the valve stem to the stem tip, and a quantity of cooling medium partly filling the head end chamber.

In testimony whereof I hereto affix my signature.
